Primary Examiner — Susan Moon Lee**CLAIM**

The ornamental design for an “imaging device,” as shown and described.

DESCRIPTION

FIG. 1 is a front right perspective view of an imaging device. FIG. 2 is a front view of the imaging device of FIG. 1. FIG. 3 is a rear view of the imaging device of FIG. 1. FIG. 4 is a right side view of the imaging device of FIG. 1. FIG. 5 is left side view of the imaging device of FIG. 1. FIG. 6 is a top view of the imaging device of FIG. 1. FIG. 7 is a bottom view of the imaging device of FIG. 1. FIG. 8 is a front left perspective view of the imaging device of FIG. 1 with an output tray extended; and, FIG. 9 is front left perspective view of the imaging device of FIG. 1 with an input tray removed and positioned adjacent the imaging device. Singular broken lines and entirely unshaded portions contained within broken lines are not claimed.
